UNITED STATES PATENT OFFICE.

JOHN P. WEAVER, OF TERRE HAUTE, INDIANA.

REEL-HOLDER.

1,204,217.

Specification of Letters Patent. Patented Nov. 7, 1916.

Application filed May 19, 1916. Serial No. 98,692.

To all whom it may concern:

Be it known that I, JOHN P. WEAVER, a citizen of the United States, residing at Terre Haute, in the county of Vigo and 5 State of Indiana, have invented certain new and useful Improvements in Reel-Holders, of which the following is a specification.

This invention relates to certain new and useful improvements in reel holders.

10 One of the objects of the present invention is to produce a simple and practical reel holder positive in operation and not likely to get out of order.

A further object is to provide a reel holder 15 having few parts, compactly arranged, which will be easy and inexpensive to manufacture.

A further object is to provide a device of 20 the above character of reduced size and greater capacity.

Other objects will be in part obvious from the annexed drawings and in part indicated in connection therewith by the following 25 analysis of this invention.

This invention accordingly consists in the 30 features of construction, combination of parts and in the unique relations of the members and in the relative proportioning and disposition thereof, all as more completely outlined herein.

To enable others skilled in the art so fully 35 to comprehend the underlying features thereof that they may embody the same by the numerous modifications in structure and relation contemplated by this invention, drawings depicting a preferred form have 40 been annexed as a part of this disclosure, and in such drawings, like characters of reference denote corresponding parts throughout all the views, in which—

Figure 1 is a sectional plan view of the 45 complete device; Fig. 2 is a central sectional view taken at right angles to Fig. 1; Fig. 3 is a detail perspective view showing the locking means; Fig. 4 is a view similar to Fig. 2 showing a modification.

In order that a clearer understanding of 50 the present invention may be had it will hereinafter be described with relation to its application to that type of reel holders particularly adapted for reeling or coiling the chain or cord connected with eye glasses. As is usual in devices of this character, the

holder is secured to the dress or coat of the wearer, and the free end of the flexible chain 55 secured to the eye glasses, it being understood that on removal of the eye glasses the chain may be easily and quickly wound upon the holder to its full extent.

Referring now to the drawings, 5 denotes 60 the base plate or member of the casing provided with a pin 6 adapted to be secured in vertical position upon the coat of the user. A cover 7 incasing the reel proper is rigidly 65 secured to the base plate in any suitable manner as by push joint 8, and it is provided with an opening 10 through which the cord or chain 11 is adapted to pass. One end of this chain 11 is provided with a hook 12 for attachment to the eye glasses, and the 70 other end, after being coiled about the winding drum, is secured to the drum at the point 13 in any desired manner.

The base plate is provided with a rigid 75 central hub 14 about which a winding drum 15 is adapted to freely rotate. This drum has a flanged periphery, as shown clearly in Fig. 2, about which the chain 11 is coiled.

Within the winding drum is a relatively 80 narrow coiled spring 16 one end of which is secured to the inner face of the periphery of the drum at the point 17, Fig. 1, and the other end is secured to a pin 18 mounted upon the under side of a cup-shaped member 20 within the drum 15 and loosely surrounding the stud 14. This cup shaped member 20 is provided also with a relatively narrow coiled spring 21, one end of which is secured to the inner face of the member 20 at the point 22, while its opposite end 90 engages a slot 23 in the upper end of the stud 14. It will thus be seen that the device includes two spiral or coiled springs which might be said to be connected in tandem, so arranged and positioned as to be tensioned simultaneously as the chain 11 is unwound from the drum. That is, a movement 95 of the connection 13 in one direction will cause a reactive movement of its opposite end connected with the stud 18 to move it 100 in the same direction, thereby causing the end 22 of the spring to move at one-half the speed of the point 13, assuming of course that the springs are equally tensioned, and in the same direction. For example, ten 105 complete revolutions of the winding drum

will place both of the springs under tension, giving each five turns. In order to hold the reel in unwound position without tension upon the chain connected with the eye glasses, suitable holding means are provided, while in the present case, Figs. 1 and 2, includes a pawl 24 pivotally mounted upon the under side of the drum. A co-acting pin 25 is mounted upon the base plate 5 adapted 10 to co-act with a suitable notch in the pawl. The pin being preferably secured in a vertical position upon the coat of the wearer will place this holding pin 25 in such position as to be engaged by the pawl 24 by the 15 action of gravity. A slight pull on the chain will move the pawl out of engagement with the detent 25, and when quickly released the pawl 24 will fly outwardly, due to centrifugal force and permit the spring to wind up 20 the chain.

The reeling may be stopped at any time by holding the chain, which will cause the pawl to drop into locking engagement by gravity at any desired point.

25 In Fig. 4 is shown a modification in which the drum instead of being provided with a depression for the locking means, the casing 5 is provided with a depression 26 in which the pawl 24 is mounted, it being pivoted to the drum and operating in a manner similar to that above described. This construction provides a larger space within the casing for the reel and springs.

30 It is believed that from the above description those familiar with the art will have no difficulty in understanding the mode of operation and manner of using a device of this character. It will be seen that the reel holder may be compactly constructed by reduction in the size of springs, yet maintain the desired capacity for fully winding the chain between the reel and the eye glasses. The invention is simple and practical in construction, inexpensive to manufacture 45 and accomplishes, among others, all of the objects and advantages herein set forth.

50 As many changes could be made in the above description and many apparently widely different embodiments of my invention could be made, without departing from the scope thereof, it is intended that all matter contained in the above description or shown in the accompanying drawing shall be interpreted as illustrative and not in a 55 limiting sense.

Having thus described my invention what I claim as new and desire to secure by Letters Patent is—

60 1. In a device of the character described, in combination, a base plate having a fixed central stud, a flanged drum loosely mounted upon said stud, a flexible member adapted to be wound thereon, a flanged holder mounted within said drum and substantially half the width thereof, and coil springs connected in

tandem between the drum and the central stud about which it rotates.

2. In a device of the character described, in combination, a base plate having a fixed central stud, a flanged drum loosely mounted upon said stud upon which a flexible member is adapted to be wound, a holder of substantially half the width of said flange mounted within said flanged drum, coil springs connected in tandem on opposite sides of the holder within the drum and acting between the drum and the central stud about which it rotates, and holding means acting between the drum and the base plate adapted to hold the reel in desired position. 75

3. In a device of the character described, in combination, a base plate having a fixed central stud, a drum loosely mounted upon said stud upon which a flexible member is adapted to be wound, a flanged holder mounted within said drum, coil springs connected in tandem between the drum and the central stud about which it rotates, and holding means acting between the drum and the base plate adapted to hold the reel in 80 desired position, said holding means comprising a pawl pivotally mounted upon the drum adapted to coact with a stud mounted upon the base plate. 85

4. In a device of the character described, in combination, a base plate provided with fastening means, a central stud mounted upon said base plate, a flanged drum adapted to rotate about said stud, a coil spring within said flanged drum adapted to rotate bodily about said stud, a holder resting upon said spring, a coiled spring mounted within said holder, said springs being arranged in tandem with the outer end of said first spring secured to the drum and its inner end secured to the holder, the outer end of said second spring being secured to said holder and its inner end secured to said central stud. 95

5. In a device of the character described, in combination, a base plate provided with fastening means, a central stud mounted upon said base plate, a flanged drum adapted to rotate about said stud, a coil spring within said flanged drum adapted to rotate bodily about said stud, a flanged holder resting upon said spring, a coiled spring mounted within said holder, said spring being arranged in tandem with the outer end of said first spring secured to the drum and its inner end secured to the holder, the outer end of said second spring being secured to said holder and its inner end secured to said central stud, and locking means operating between the base plate and the holder adapted to hold the reel in any desired position of winding. 110

6. In a device of the character described, in combination, a base plate having a fixed central stud, a drum loosely mounted upon 115

said stud, a flexible member adapted to be wound thereon, a holder mounted within said drum, and coil springs connected in tandem between the drum and the central 5 stud about which it rotates, said base plate being provided with a depression and a locking means within said depression.

In testimony whereof I affix my signature in presence of two witnesses.

JOHN P. WEAVER.
